UNITED STATES PATENT OFFICE

EDGAR O. LOEBER, OF CLEVELAND HEIGHTS, OHIO, ASSIGNOR TO THE LOME COMPANY,
OF CLEVELAND, OHIO, A CORPORATION OF OHIO

CLOSURE

Application filed October 31, 1929. Serial No. 403,691.

The present application relates, as indicated, to closures, and more particularly to dog-proof closures for garbage and trash cans. The primary object of the invention is to provide a closure for use with containers, the closure being of such character that it can be removed from the container only when a latch element is moved into proper position. A further object of the invention is to provide a device of the character described which shall be unusually simple and inexpensive and yet which shall have an unusually efficient operation. Further objects will appear as the description proceeds. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is an elevation, partly in section, of a container having a closure of my present invention applied thereto; Fig. 2 is a bottom plan view of a closure constructed in accordance with my invention; Fig. 3 is an elevation thereof; Figs. 4 and 5 are fragmental sections of details of construction; and Fig. 6 is a fragmental section of the latch mechanism forming a part of my invention.

Referring more particularly to the drawing, it will be seen that I have shown a container 10 having a rolled edge forming an outwardly projecting flange 11 at its upper open end. The closure 12 of my invention is provided with a depending flange 13 adapted to overlie and enclose the projection 11. Said flange 13 is provided at two or more spaced points with inwardly projecting lugs 14 adapted to engage under the flange 11.

At a point on the opposite side of the periphery of the flange 13 of the projections 14, said flange 13 is formed with an aperture 15, the vertical dimension of said aperture being somewhat greater than the horizontal dimension thereof. To the upper surface of

the closure 12, and in line with the aperture 15, there is secured a block 16 having a tongue 17 projecting toward the periphery of the closure, said tongue being bent upwardly intermediate its ends and downwardly at its free end 18. Preferably, the closure 12 is so formed that the end 18 of the tongue 17 may project below the upper level of a shoulder 19 formed on said closure 12.

A latch member 20 is formed at its one end 21 with an aperture adapted to receive the end 18 of the tongue 17, whereby the end 21 of the latch member 20 is hinged to the closure 12. Said latch member 20 is curved to clear the shoulder 22 of the closure 12, and the free end 23 of said latch member extends through the aperture 15 from the outer to the inner side of the flange 13.

It will be noted that the width of the aperture 15 is less than the width of the latch member 20. The opposite edges of the member 20 are cut away as at 24 adjacent the end 23 thereof, thereby forming a pair of shoulders 25 somewhat removed from the end 23 and another pair of oppositely facing shoulders 26 at the extremity of the latch member 20. In assembling the device, the latch member is turned to such a position that the width thereof corresponds to the larger dimension of the aperture 15, and the shoulders 26 are inserted through said aperture. Thereafter, the latch member is rotated through 90° so that the shoulders 26 engage behind the flange 13 and intersect the same in a line extending transversely of the smaller dimension of the aperture 15. Thereafter, the tongue 17 is entered in the aperture in the end 21 of the latch member 20 and the block 16 is secured to the closure 12 through the medium of screws or bolts 27.

Said screws serve also the function of securing to the block 16 a leaf spring 28 which projects outwardly toward the periphery of the closure, and the outer end 29 of which bears upon the latch member 20 to urge the same into the position of Fig. 6.

As will be seen, when the latch member 20 is in the position of Fig. 6, the end 23 thereof is in such a position as to engage the flange 11 of the container 10 in case it is at-

tempted to lift the closure 12 off of said container. In this position, the shoulders 25 engage the outer surface of the flange 13 to prevent further movement downwardly of the handle member 20. In case it is desired to remove the closure from the container 10, the handle 20 is grasped and, by reason of the position of the same on the closure 12, the handle is rotated about its hinged connection 10 with the tongue 17 until the shoulders 26 engage the inner surface of the flange 13, it being understood that the spring 28 is of insufficient strength to prevent such rotation of the latch member when the weight of the closure 12 is borne thereon. Such movement of the latch member moves the end 23 thereof out of interfering relation with the flange 11, and the edge of the closure 12 to which the latch member 20 is secured is raised. 20 Thereafter, the closure may be moved in such manner as to release the engagement of the lugs 14 with the flange 11 so that the closure may be bodily removed from the container.

Of course it will be understood that, in place of the lugs 14 formed by indentation of the flange 13, as shown in Fig. 4, I may use a lug 14' comprising a separate member spot welded or otherwise secured to the internal surface of the flange 13.

30 Other modes of applying the principle of my invention may be employed instead of the one explained, change being made as regards the mechanism herein disclosed, provided the means stated by any of the following claims 35 or the equivalent of such stated means be employed.

I therefore particularly point out and distinctly claim as my invention:

1. In combination with a receptacle having laterally projecting means at its open end, a closure having a depending flange adapted to overlie and enclose said projecting means, a latch carried by said closure and extending through said flange, and a spring 40 in direct engagement with said latch and urging said latch into position to engage said projecting means to prevent removal of said closure.

2. In combination with a receptacle having laterally projecting means at its open end, a closure having a depending flange adapted to overlie and enclose said projecting means, a handle pivoted to said closure and having 50 a portion thereof extending through said flange, and a spring urging said portion into position to engage said projecting means, the strength of said spring being insufficient to hold said handle portion in engaging position when the weight of said closure is supported by said handle.

3. In combination with a receptacle having laterally projecting means at its open end, a closure having a depending flange 55 adapted to overlie and enclose said projecting

means, means on said flange engageable with said projecting means, a latch carried by said closure and extending through said flange, and a spring in direct engagement with said latch and urging said latch into position to engage said projecting means to prevent removal of said closure. 70

4. As a new article of manufacture, a receptacle closure having a depending flange formed with an aperture therein, a combined 75 handle and latch having its one end pivoted to said closure and having its opposite end extending through said aperture, said last-named end being formed with a shoulder engageable with the external surface of said flange, and a spring urging said shoulder into engagement with said flange. 80

5. As a new article of manufacture, a receptacle closure having a depending flange formed with an aperture therein, a combined 85 handle and latch having its one end pivoted to said closure and having its opposite end extending through said aperture, said last-named end being formed with a shoulder engageable with the external surface of said flange, a spring urging said shoulder into engagement with said flange, and means to prevent removal of said handle end from said aperture. 90

6. As a new article of manufacture, a receptacle closure having a depending flange formed with an aperture therein, a combined handle and latch having its one end pivoted to said closure and having its opposite end extending through said aperture, said last-named end being formed with a shoulder engageable with the external surface of said flange, a spring urging said shoulder into engagement with said flange, and a second shoulder on said handle end engageable with 100 the internal surface of said flange. 105

7. As a new article of manufacture, a receptacle closure having a depending flange formed with an aperture therein, a combined handle and latch having its one end pivoted 110 to said closure and having its opposite end extending through said aperture, said last-named end being formed with a shoulder engageable with the external surface of said flange, a spring urging said shoulder into engagement with said flange, and a second shoulder on said handle end engageable with the internal surface of said flange, the strength of said spring being such as normally to hold said first-mentioned shoulder in engagement with the external surface of said flange, but to permit said last-mentioned shoulder to engage the internal surface of said flange when the weight of said closure is supported by said handle. 115 120 125

Signed by me this 28th day of October, 1929.

EDGAR O. LOEBER.
